UNITED STATES PATENT OFFICE.

MAX H. METAL, OF NEW YORK, N. Y.

COIN-REGISTERING CASE OR RECEPTACLE.

1,032,760.

Specification of Letters Patent. Patented July 16, 1912.

Application filed October 2, 1911. Serial No. 652,339.

To all whom it may concern:

Be it known that I, MAX H. METAL, a citizen of the United States of America, residing in New York, borough of Brooklyn, county of Kings, and State of New York, have invented certain new and useful Improvements in Coin-Registering Cases or Receptacles, of which the following is a specification.

10 This invention relates to an improved coin-registering case or receptacle in which a certain number of coins can be successively inserted, the case being automatically locked after the insertion of the first coin and held 15 in locked position until a predetermined number of coins are inserted, after which the case is automatically unlocked and opened for the removing of the coins.

In the accompanying drawings, Figures 1 20 and 2 represent my improved coin-registering case or receptacle, respectively in open and closed position, Fig. 3 is a front-view with the face-plate removed, showing the interior mechanism, Fig. 4 is a rear-elevation of Fig. 3, with the rear-plate being removed, and Figs. 5 and 6 are vertical transverse sections, respectively on line 5—5, Fig. 1, and 6—6, Fig. 3, and Fig. 7 is a horizontal section, on line 7—7, Fig. 3.

30 Similar letters of reference indicate corresponding parts throughout the several figures of the drawings.

This invention comprises a telescoping coin registering receptacle.

35 Referring to the drawings, *a* represents an outer box, which is open at its lower end, closed at its upper end and provided in the upper end with a slot *a*¹ for inserting a dime or other suitable coin to be collected. The 40 front-plate of the outer box *a* is provided with a window opening *o* for exposing the numbers on a rotating registering-disk *d*. This disk turns on a center-pivot *d*¹ between the front and rear plates of the box *a*, said 45 disk being provided on its front-face with the numerals 10 to 90, at intervals of 10, arranged equidistantly from each other and in a circle concentric with the axis of the disk so that when the disk is turned these numbers are shown successively through the opening *o*. The disk *d* is also provided with as many teeth or projections *e* and intermediate slightly-concave depressions *e*¹ between the same as there are numbers on the disk. Over the disk extends a bridge-plate 50 *a*² that serves as a guide-plate for the disk and for the coins inserted into the case. One of the depressions on the disk is engaged by the free end of a check-spring *f* that is attached to one of the corner-pins *f*¹ of the 60 frame. The disk *d* is further provided on the rear-face, that is, the face opposite to that carrying the numbers, with a laterally projecting circumferential rim or flange *g* having a notch *g*¹ at one point of its circumference.

65

An inner slide-box *h* having an open top and a closed bottom is adapted to slide in the box *a* constituting a telescopic coin holder. The bottom *h*¹ of this inner slide-box constitutes the bottom of the coin receptacle when the boxes are slid together to form a closed receptacle and the inner box is provided with an opening in its lower part through which the coins may be removed when the inner box is slid out and the receptacle expanded. This opening is 70 preferably formed by omitting the front wall of the box *h*. The rear wall of the box *h* is provided with a longitudinal slot *h*¹ which is engaged by a transverse stud *h*² in the outer box *a*. This stud serves as a stop for the inner box *h* at the ends of its sliding movement as indicated in Figs. 3 and 4. The rear wall of the box *h* is provided at its 75 upper end with a lateral lug *h*³ arranged to pass through the notch *g*¹ in the disk *d* in the inward and outward sliding of the box *h* when said wheel is in the position to bring said notch at the lowest point in the 80 rotation of the wheel as indicated in Fig. 4. When the box is closed and after the first coin is inserted this lug engages the inner edge of the lateral circumferential flange and the box *h* is thereby held in inward 85 closed position until the disk *d* completes its rotation. The lateral lug *h*³ is preferably formed by swaging a lateral notch in the upper edge of the back plate of the box *h*. The inner box *h* slides freely in the outer 90 box *a* to open or close the coin receptacle except when the lug of the inner box is in engagement with the inner face of the lateral flange of the registering disk in the outer box. When the notch *g*¹ is in position to permit the opening and closing of the coin receptacle, the disk *d* shows zero at the window *o*. The corner pin *f*¹ near the coin slot *a*¹ in the top of the outer box serves as 95 an abutment for guiding the coin into the receptacle and aids in completing a full step of rotation of the disk *d*.

100

105

110

The operation of my improved coin-registering case or receptacle is as follows: The registering disk d is set at its initial position by rotating it to bring the zero mark 5 opposite the window o and the notch g^1 is then at the lowest point of the disk as shown in Fig. 4. The inner box h is then pushed in closing the coin receptacle, the lateral lug h^3 passing through said notch. A dime, if 10 the device is to be used for dimes, is then inserted through the drop-slot a^1 in the upper end of the box a and pushed down so that it rests on and presses one of the depressions of the disk, then at the upper part of the 15 box, so as to turn the same, while the successive pressure exerted on the coin moves it against the corner-pin f^1 and completes the partial rotation of the disk and permits the dropping of the coin into the lower part of 20 the receptacle. The turning of the disk d brings the body of the lateral flange g underneath the lug h^3 , the lower end of which is preferably rounded, and the inner box h is thus locked against outward movement. 25 The registering disk being turned in the direction of the arrow, the same is shifted sufficiently to exhibit the number 10 through the observation-opening o . Every time a new coin is inserted the registering disk is 30 shifted for a distance of one tooth until gradually the disk has made a complete rotation when the notch in the rim of the disk again arrives in line with the lug h^3 and the inner box is automatically released and the 35 receptacle can be opened for the removal of

the coins. The several numerals on the registering disk d show successively through the observation-opening o and indicate thereby at all times how much money there is in the case. This improved registering 40 attachment can be arranged for coins of other than the 10 cent denomination by increasing the size of the case and registering disk in proportion to the number and size of the coins to be inserted in the case or receptacle.

I claim:

A telescopic coin registering receptacle comprising an outer box having a closed top and an open bottom and provided with a 50 coin slot, a registering disk disposed within said box adjacent to said coin slot and provided with a lateral flange having a notch, and an inner box sliding in said outer box and having an open top and a closed bottom. 55 and provided near its upper end with a lateral lug engaging the inner edge of said flange for locking the receptacle in contracted closed position during the rotation of the disk, said notch permitting the boxes 60 to expand into open position when the registering disk reaches a certain point in its rotation.

In testimony that I claim the foregoing as my invention I have signed my name in 65 presence of two subscribing witnesses.

MAX H. METAL.
